TILTING APPARATUS

Donald H. Mitchell, Cranford, N. J., assignor to
Western Electric Company, Incorporated, New
York, N. Y., a corporation of New York

Application November 16, 1943, Serial No. 510,498

8 Claims. (Cl. 248—139)

This invention relates to tilting apparatus, and more particularly to apparatus for tilting heavy articles from one position to another.

An object of the invention is to provide a simple, efficient and practical apparatus for tilting heavy articles.

With this and other objects in view, the invention comprises a tilting apparatus having a body pivotally carrying an article supporting element, with interconnecting means between the body and element to limit the movement of the element and article in one direction and lock them in a given position relative to the body.

Other objects and advantages will be apparent from the following detailed description when considered in conjunction with the accompanying drawings, wherein

Fig. 1 is a side elevational view of one species of the invention;

Fig. 2 is an end elevational view of the structure shown in Fig. 1;

Fig. 3 is a fragmentary side elevational view of another species of the invention, and

Fig. 4 is an end elevational view of the structure shown in Fig. 3.

Referring now to the drawings, attention is first directed to Figs. 1 and 2, which illustrate a body, indicated generally at 10, which is rectangular in general contour. Specifically, the body 10 includes spaced side members 11, with vertical members 12 secured thereto at the corners of the body. End plates 14 and 15 are fixed to the vertical members 12 and, through the aid of angle brackets 16, the body member 10 may be secured to any suitable support (not shown). The corner members 12 adjacent the end plate 14 have the ends of a cross bar 18 fixed thereto, the latter serving as a rest for the free end of an article supporting element 19. A pivot rod 20 is supported by the upper ends of the corner members 12 adjacent the end plate 15, the rod 20 pivotally supporting the element 19 through the aid of bearing members 21.

The element 19 has spaced article supporting blocks or members 23 mounted upon the upper surface thereof, as shown, these members being of the contour illustrated in Fig. 2, recessed as at 24 to receive a cylindrical article 25. Flexible bands 26 each have one end fixed to their respective members 23 at tapered sides 27 thereof, loops 28 being formed in the opposite ends of the bands to receive and be connected to tightening bolts 29. Brackets 30, of the contour shown in Fig. 2, are secured to each of the members 23, the brackets being notched to removably receive

the bolts 29 and having transversely extending portions 32 against which washers 33 and wing nuts 34 may press during the tightening of the holding means including the flexible bands 26, the bolts 29, and the wing nuts and washers. In the present embodiment there exists an aperture in the article 25 at a position where it is adapted to receive a locating pin 36 carried by the central or right hand member 23. Through the aid of the pin 36, the article 25 may be accurately located on the members 23 of the element 19. Other members 38 of the contour shown in Fig. 2, rigidly mounted upon the element 19 at the pivot end thereof, serve in locating the article 25 in place upon the members 23 and to further assist in supporting the element when moved into a vertical position.

Latching elements 40, of the contours shown in Fig. 1, are secured to their respective portions 20 of body members 11 and cooperate with a U-shaped latch 41, having the ends of its legs pivotally supported by the ends of a shaft 42 extending through and carried by the element 19.

Referring now to the latching elements 40, it 25 will be noted that they are provided with cam surfaces 43 upon which the central portion of the latch 41 will ride during movement of the element 19 with the article into the vertical position shown in dot and dash lines in Fig. 1. After 30 riding over the cam surfaces 43 the latch 41 will drop into retaining notches 44 through the assistance of other cam surfaces 45. The weight of the article, when in the vertical position, will cause the latch 41 to be retained in the notch 44, a shoulder 46 eliminating accidental return movement of the article and element to its horizontal position.

Considering now the function of this embodiment of the invention, let it be assumed that the 40 retaining bolts 29 and their bands 26 are moved to positions where they will not interfere with the placing of the article 25 on the members 23, that is, in the recessed portions 24 thereof. Through the assistance of the pin 36 and members 38, the article is located in the members 23. The article is then secured in place, where the positioning of the bands 26 over the article and the tightening of the wing nuts of the bolts 29 in engagement with their respective portions 32 of their brackets 30 takes place. It will be noted that the latch 41, that is, the central portion thereof, normally rests upon the upper body members 11 and rides upon these members during movement of the element 19 with the article about its pivot rod 20, from the solid line position

(Fig. 1) to the dot and dash line position shown therein. During this movement the latch will be guided through the cam surfaces 43 and 45 into the notches 44 of the elements 40, automatically locating the article in a vertical position and holding the article thus for a desired length of time. If desired, the article may be removed from the element 19 in the vertical position. This may be accomplished by loosening the wing nuts 34 sufficiently on their bolts 29 so that the bolts may be removed from the brackets 30, freeing the holding bands 26 from the article and allowing the article to thus be removed through the aid of a truck or other suitable conveying means. To return the element 19 to its horizontal position, the latch 41 may be manually moved free of the notch 44 of the elements 40.

The structure shown in Figs. 3 and 4 is substantially identical with the structure shown in Figs. 1 and 2 with the exception that the body, which in these figures is indicated generally at 50, is provided with an extension 51 and supporting units 52, including rollers, wheels or the like 53, fixed thereto. Here the body 50 includes elements 54 identical in every detail to the elements 40, with cam surfaces 55 and 56 and retaining notches 57 for receiving a latch 58 identical with the latch 41. An article supporting element indicated at 59 is identical in every detail with the element 19 together with its supporting members 60 and locating members 61. Here the element 59 is pivotally supported by a shaft 62 for its movement from the horizontal position to the vertical position.

In this embodiment the article may be transported from one position to another in either the vertical or horizontal positions and the article may further be moved in the same manner as described regarding the structures shown in Figs. 1 and 2, from the horizontal position to the vertical position, and when in the latter position the article may be released and allowed to come to rest upon an upper surface 64 of the extension 51.

Although specific improvements of the invention have been shown and described, it will be understood that they are but illustrative and that various modifications may be made therein without departing from the scope and spirit of this invention as defined by the appended claims.

What is claimed is:

1. A tilting apparatus comprising a body, an element for supporting an article pivotally carried by the body, a latch carried by the element and movable therewith in a given direction during movement of the element from its normal position, and means disposed in the path of the latch while the latch is moving in the said given direction to cause the latch to stop movement of the element in the given direction and hold the element against movement from the stopped position in either direction.

2. A tilting apparatus comprising a body, an element for supporting an article pivotally carried by the body, a latch pivotally carried by the element and having a portion adapted to ride on the body during movement of the element in a given direction from its normal horizontal position, and means disposed in the path of the said latch portion to cause the latch to stop movement of the element in the given direction and at a predetermined position.

3. A tilting apparatus comprising a body, an

element for supporting an article pivotally carried by the body, a latch pivotally carried by the element and having a portion adapted to ride on the body during movement of the element in a given direction from its normal horizontal position, and a member carried by the body disposed in the path of the said latch portion and formed to cause the latch to stop movement of the element in the given direction beyond a predetermined position and hold the element against movement from the said position in either direction.

4. A tilting apparatus comprising a body, an element for supporting an article pivotally carried by the body, a latch pivotally carried by the element and having a lateral projection to ride on the body during movement of the element from its normal horizontal position, and a control member carried by the body and having notch therein, to receive the lateral projection to stop movement of the element from its horizontal position and a portion disposed in the path of the latch projection to direct it into the notch.

5. A tilting apparatus comprising a body, an element for supporting an article pivotally carried by the body, a latch pivotally carried by the element and having a lateral projection to ride on the body during movement of the element from its normal horizontal position, and a control member carried by the body and having a notch therein, to receive the lateral projection to stop movement of the element from its horizontal position, and a cam surface disposed in the path of the latch projection to direct it into the notch.

6. A tilting apparatus comprising a body, an element for supporting an article pivotally carried by the body, a U-shaped latch having its legs pivotally carried by the element and its central portion positioned to ride on the body during movement of the element from its normal horizontal position, and a control member, carried by the body, with a notch for receiving the central latch portion to cause the latch to stop the element in a given position and with a cam surface to direct the central latch portion into the notch.

7. A tilting apparatus comprising a body, an element for supporting an article pivotally carried by the body, a latch pivotally carried by the element and having a portion adapted to ride on the body during movement of the element from its normal position, and a control member, carried by the body, with a notch, having parallel vertical walls for receiving the latch portion to cause the latch to stop the element and hold it against displacement in a given position and with a cam surface to direct the latch portion into the notch.

8. A tilting apparatus comprising a body, an element for supporting an article pivotally carried by the body, means carried by the body to support the element in a lateral position, a latch pivotally carried by the element and having a portion positioned to ride on the body during movement of the element from its lateral position to a vertical position, and a control member carried by the body and having a notch therein, a cam surface to cause the latch portion to ride up to the notch and a cam portion positioned to force the latch portion into the notch.
